UNITED STATES PATENT OFFICE.

AUGUSTINE DAVIS, JR., AND ARTHUR L. BETTS, OF CINCINNATI, OHIO; SAID BETTS
ASSIGNOR TO SAID DAVIS.

CAN.

Application filed August 16, 1922, Serial No. 582,126. Renewed January 17, 1925.

To all whom it may concern:

Be it known that we, AUGUSTINE DAVIS, Jr., a citizen of the United States, residing at Cincinnati, in the county of Hamilton and State of Ohio, and ARTHUR L. BETTS, a citizen of the United States, residing at Cincinnati, in the county of Hamilton and State of Ohio, have invented certain new and useful Improvements in Cans, of which

10 the following is a specification.

The invention relates to can structures and the like and provides in particular a strong, durable, non-leaking and non-deformable large-size carrying can suitable for lubricating oil and other liquids, the features of construction being useful for tank-wagon measuring buckets and other heavy construction sheet metal vessels.

15 In the accompanying drawings, forming a part hereof:

Fig. 1 is an elevation of a can embodying the invention, the upper part being shown partially broken away and in section;

20 Fig. 2 is an enlarged vertical section through the joint between the breast and shell;

Fig. 3 is a similar section through the joint between the shell and the bottom head; and

25 Fig. 4 is an inside face view of a portion of the neck, showing a capacity level indicator.

The can has a cylindrical shell 1 stiffened by vertical corrugations 2, which stop short of the upper and lower ends. 3 is a breast, the proximate portions of the breast and shell being received one within the other to form two thicknesses united and supporting each other in the manner which will be more

30 particularly described.

The sloping top of the breast is reinforced by radial corrugations 4 extending nearly to the periphery. Outside the ends of these corrugations is a plain arched shoulder 5, and depending from the shoulder a long flange 6. The flange 6 encloses the upper portion of the cylindrical shell, forming a belt of double thickness around this part of the can, and the lower end of the flange is

joined to the outer face of the shell by a continuous autogenous weld 7, making an integral leakless joint. Above the weld and below the shoulder the two thicknesses of the shell and breast flange are rolled out to form an arched bead 8, which both strengthens the side of the can and protects the weld. The upper end 9 of the shell rises upward from the inner thickness of the bead and is arched inward at 10 to form a seat which underlies and sustains the shoulder 5, in a manner very effectively to enable the breast to withstand the rough usage to which it is subject. The combination of the upwardly and outwardly facing arched shoulder of double thickness, above and inward of an outwardly projecting double thickness arched bead, the latter overhanging a continuous integral weld, forms a non-leaking structure of maximum strength at the widely overlapping junction between the breast and shell.

35 A cylindrical neck 11 of comparatively heavy metal is welded at its lower end into the flanged-up top opening of the breast, and is adapted to receive a screw or other closure 12, preferably connected to the breast by a shackle loop 13 and chain 14. 40 15 is a handle fixed to the breast.

An arched bottom or bottom head 16 is set into the lower end of the shell, this head having a downwardly directed flange 17 which fits within the end of the shell, the two edges being side by side. These edges are united by a continuous autogenous weld 18 forming a tight joint. A ring 20 of comparatively heavy gauge bent to present a short inner limb 21 and a long outer limb 22, in cross-section, embraces the welded edges aforesaid, and the three thicknesses composed of its outer limb, the lower portion of the shell encircled thereby and the bottom flange in turn encircled by the shell are rolled to form an outwardly projecting bead 19. The weld is thus protected and the ring is locked in place by the strengthening bead. The portion of the heavy ring which extends below and inwardly beneath the welded edges of the shell and bottom

flange constitutes the extreme foot of the can, guarding the welded joint from abrasion and other wear. While this portion is shown folded upwardly within the flange, we do not limit ourselves to this precise form.

Within the neck 11 is placed a capacity level indicator 23. Said indicator comprises a bent retainer plate 24 fixed at the 10 sides to the inside of the neck, and a gage plate which initially is adjustable vertically behind the retainer plate. The lower end of the gage plate is bent inward to form a foot 25 specially adapted for visible contact with the surface of the liquid, and when at the manufactory the can has been filled with its rated capacity of liquid the gage plate is adjustable until the foot just touches the liquid, after which this plate is brazed 20 or otherwise fixed in this position.

The bead 19 projecting outward beyond the lines of the can not only greatly stiffens the structure of the foot of the can, but constitutes an unyielding guard against deformation by lateral blows. Cans of this character are carried in racks or in enclosures on moving vehicles. Such racks are deep enough to prevent the cans from toppling over and falling out of them, but it is not 30 practicable to make the cans and the racks of such relative dimensions that the cans would be a snug lateral fit in the racks, and thus prevent the cans being slammed back and forth between the sides of the racks. 35 The introduction of the bead in the three thicknesses of metal, including the heavy reinforcing band, at the bottom of the can, affords a very strong projecting element to take on its arch the main force of the impact 40 when the can slides across the bottom of the rack and comes up against the opposite side, thereby protecting the thinner metal of the shell from damage.

The bead 8 at the upper portion of the 45 can affords somewhat of the same type of protection if the racks are deep enough to reach this height on the cans.

As these cans are made accurately to size, and calibrated so that they may be used as 50 accurate measures, it is important that they be protected as thoroughly as possible from anything likely to cause dents in the can, which would alter the capacity sufficiently to make them useless as measures.

55 What is claimed as new is:

1. A can having a cylindrical shell and an inwardly sloping breast, the latter having a flange extending downward from its lower portion, said flange and the upper portion 60 of the shell being overlapped forming a belt of double thickness, a continuous weld uniting the edge of the outer overlapping part to the face of the inner, and a circumferential bead formed in the double-thickness belt 65 protecting the weld.

2. A can having a cylindrical shell, an inwardly sloping breast having a downwardly-extending flange enclosing the upper portion of the shell, a continuous weld uniting the breast flange to the outer face of the 70 shell, and a bead rolled in the overlapped shell and breast flange above the weld.

3. A can having a shell and a breast having a flange enclosing the upper portion of the shell and welded thereto, a bead rolled 75 out in two thicknesses of metal the upper end of the shell rising upward above the bead and having an inwardly extended seat supporting the breast.

4. A can having a shell, and a breast having a corrugated slope, a plain arched shoulder and a flange enclosing and united to the upper portion of the shell, a bead rolled out in the two thicknesses of metal below the 80 shoulder, the upper end of the shell rising upward above the bead and having an inwardly arched seat supporting said shoulder.

5. A can having a shell, a breast having a flange enclosing the upper portion of the shell, a continuous weld uniting the lower 85 end of the breast flange to the outer face of the shell, and a bead rolled in the shell and breast flange above the weld and below the upper end of the shell, the shell having an inwardly arched seat rising above the 95 bead to support the shoulder of the breast.

6. A can having a shell, a breast having a flange enclosing the upper portion of the shell, said breast having a radially corrugated slope and a plain arched shoulder connecting said slope with the base of the flange, a continuous weld uniting the breast flange to the face of the shell, a bead forced outward in the shell and breast flange above 100 the weld and below the upper end of the shell, and an inwardly arched seat formed from the upper end of the shell above the bead to underlie and support said shoulder.

7. In a measuring can or bucket, a shell, a bottom head having a downturned flange set into the lower portion of said shell, a continuous weld uniting the lower edges of the shell and flange, a heavy reinforcing ring encircling the lower portion of the shell and said flange, said ring having a portion extending below said weld, and a bead forced outward beyond the lines of the can 115 in the three thicknesses of the ring, shell and flange above the weld.

8. In a measuring can or bucket, a shell, a bottom head having a downturned flange set into the lower portion of the shell, a weld forming a tight bottom joint, a heavy reinforcing ring encircling the lower portion of the shell and said flange, said ring having a portion extending beneath the edge of the shell and flange, and a bead forced outward 125 beyond the lines of the can in the thicknesses of the ring, shell and flange.

9. A welded sheet-metal can or the like of

heavy construction having a cylindrical shell and an inwardly sloping breast in separate pieces, the shell being overlapped by a flange on the breast forming a belt of double thickness in which an arched bead is rolled outward above a continuous weld uniting the breast flange to the outside of the shell, said breast having an arched shoulder above the bead, and the upper portion of the shell rising above the bead and turned inward to form an arched seat for the arched shoulder.

AUGUSTINE DAVIS, JR.
ARTHUR L. BETTS.
